(57) **CLAIM**

The ornamental design for a bicycle carrier as shown and described.

DESCRIPTION

FIG. 1 is a top, front, right perspective view of a bicycle carrier showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a partially enlarged and cross-sectional view thereof; and,

FIG. 9 is a top, front, right perspective view showing the bicycle carrier in use.

The broken lines in the drawings illustrate portions of the bicycle carrier which form no part of the claimed design. The bicycle carrier is shown with symbolic break lines drawn in dot-dash broken lines in its width and height. The symbolic break lines and the appearance of any portion of the article between the symbolic break lines forms no part of the claimed design.
